(57) **CLAIM**

(**) Term: **15 Years**

The ornamental design for a combined root canal meter with high frequency treatment module, as shown and described.

(21) Appl. No.: **35/510,838**

DESCRIPTION

(22) Filed: **Nov. 6, 2020**

1. Combined root canal meter with high frequency treatment module

1.8 : Back perspective view 1

1.9 : Back perspective view 2

1.10 is a perspective view shown in an environment.

The article is equipment for measuring and displaying a root canal length of a tooth during root canal treatment which is a type of dental treatment methods; in addition, the article has a high-frequency treatment module, and is capable of performing high-frequency treatment such as cauterization of an interior portion of a tooth; the article can measure/display the root canal length and display the operation condition and the like during the high-frequency treatment; the parts shown by means of broken lines in the reproductions are not part of the claimed design; the part having oblique parallel lines in the reproduction 1.10 is transparent; the oblique parallel lines themselves shown in the reproduction 1.10 are for illustrative purposes only and form no part of the claimed design.

In Reproduction 1.10 the oblique lines are for the purpose of illustrating environment only and form no part of the claimed design.
